U.S. Appl. No. 29/634,946, filed Jan. 25, 2018, Davis.

Primary Examiner — Kelley A Donnelly(74) Attorney, Agent, or Firm — Workman Nydegger(57) CLAIM

The ornamental design for a storage unit, as shown and described.

DESCRIPTION

FIG. 1 is a front perspective view of a storage unit;
 FIG. 2 is a front elevation view thereof;
 FIG. 3 is a back elevation view thereof;
 FIG. 4 is a top plan view thereof;
 FIG. 5 is a bottom plan view thereof;
 FIG. 6 is a left elevation view thereof; and,
 FIG. 7 is a right elevation view thereof.
 The dash-dash broken lines are for illustrative purposes only and form no part of the claimed design.
